CARL W. PURKEY, OF DETROIT, MICHIGAN.

DRAFTING-TABLE.

1,077,998.

Specification of Letters Patent. Patented Nov. 11, 1913.

Application filed February 10, 1913. Serial No. 747,234.

To all whom it may concern:

Be it known that I, CARL W. PURKEY, a citizen of the United States, and a resident of Detroit, in the county of Wayne and State of Michigan, have invented a new and useful Drafting-Table, of which the following is a specification.

This invention relates to the construction of tables for draftsmen, and its object is to provide a table with adjustable retaining means for the drawing paper, so constructed, that sheets of greater or less length may be retained by the same in substantially flat condition, and be moved up or down on the board as desired.

This invention consists, in combination with the frame and a roller at each end of the same, of a chain-wheel at each end of each roller, chains extending around the chain-wheels, one at each side of the table near the edges, and adjustable paper holders extending across between the chains.

This invention further consists of means for adjusting the distances between the chain-wheels and in the details of construction of the paper holder, as fully shown in the accompanying drawings and set forth in the claims.

In the accompanying drawings Figure 1 is a plan of the drawing board. Fig. 2 is a section of the same on the line 2—2 of Fig. 1. Fig. 3 is a similar section on a larger scale. Fig. 4 is a plan showing the construction of the connection between the paper holders and the chain. Fig. 5 is a plan of a portion of the lower member and Fig. 6 is a plan of a similar portion of the upper member of the paper holders. Fig. 7 is a section on the line 7—7 of Fig. 6. Fig. 8 is a section of the wheel for turning the rollers. Fig. 9 is an elevation and Fig. 10 a section of the bearing of the upper roller. Fig. 11 is an elevation and Fig. 12 a section of the bearing for the lower roller. Fig. 13 is an elevation and Fig. 14 a plan of the chain.

Similar reference characters refer to like parts throughout the several views.

While the words "plan" and "elevation" are used in this description, these words are only relative terms as the table may be used in almost vertical position if desired.

The structure is made up of side pieces 1, between which a board 2 extends. These side pieces and board constitute the table proper and may be supported in any manner

desired. In the upper ends of the side members 1 are mounted bearings 3 for the shafts 4, which extend from the hubs 5 on which the wheels 6 are either formed or secured. 60 These hubs 5 have enlargements 7 which are secured in the roller 8, as shown in section in Fig. 12, the lower roller 8 being an absolute duplicate of the upper one and the shaft 4 of the lower roller being the same as the 65 shafts 4 of the upper roller, and the right-hand shaft 9 of the lower roller also being the same with the sole exception that it is longer and has a wheel 10 secured to it so that the lower roller may be turned. The 70 lower roller shafts 4 and 9 are journaled in blocks 26 slideable in the frames 27 secured in proper slots in the lower ends of the side members 1, and adjustable by means of the screws 28 in the usual well known manner. 75 In Fig. 1 these screws are shown turned out in order to carry the roller down to its lower limit in order to tighten the chains 13. If this adjustment is not sufficient, then the screws 28 must be turned in in order to slack 80 the chains and a few links removed from the same.

The side members 1 have grooves 11, in the bottom of which a thin plate 12 of steel may be mounted in order to avoid the 85 cutting or wearing down of the wood of the side members 1 by the chains 13 which extend around the chain-wheel 6. The side members 1 are also preferably formed with grooves 14 in their lower sides to receive 90 these chains. As shown in Fig. 14, the heavy links 15 of the chains 13 are formed with screw-threaded holes 16 to receive the screws 17 which pass through plates 18, as shown in Fig. 4. To these plates 18 are secured, 95 preferably by rivets 30, the thin strips of metal 19, preferably steel, which are formed with upstanding pins or teeth 20 as shown in Fig. 5. Secured to these strips 19 are other strips 22 of the same width formed 100 with holes 23 into which the teeth 20 may project. The upper plates are held in position by means of a screw 24 at each end which enter the holes 25 in the strips 19 and the plates 18.

When it is desired to secure a sheet of paper 29 in position, a screw 24 of each strip 22 is removed and the strips 22 swung out from across the board 2, after which the paper may be secured in position by pressing down the paper on the pins or teeth 20. The upper strips 22 are then swung back

105

110

so that the pins or teeth will project into the holes 23, after which the screws 24 are replaced to hold the upper strips in position.

- 5 5. So long as the paper is so short that it need not pass around either roller, the screws 17 remain in the inner ends of the slots 31, as shown in Fig. 1. But when the paper is to pass around either roller, the screws 17 of the adjacent paper holder will be loosened so that they may slip in the slots 31, for the pitch line of the chain wheels is of less diameter than the rollers. If the paper is to pass around both rollers, both paper holders 10 will be released. By making the connection between the paper holders and chains adjustable, a very convenient and effective 15 drafting table is produced.

I claim.

- 20 1. In a drafting table, the combination of a flat structure, rollers and chain wheels mounted adjacent the ends of the flat structure, a pair of chains extending around said chain wheels, and adjustable paper holders 25 extending across the board and connected to the chains.
2. In a drafting table, the combination of parallel side members and a board extending between them, rollers and chain wheels mounted adjacent the ends of the side members, a pair of chains extending around said 30 chain wheels, and two paper holders each

formed of two thin plates extending across the board and connected to the chains.

3. In a drafting table, the combination of 35 parallel side members and a board extending between them, rollers and chain wheels mounted adjacent the ends of the side members, a pair of chains extending around said chain wheels, and two paper holders extending 40 across the board and connected to the chains, each formed of two thin strips of metal, one of the strips having perforations and the other strip formed with teeth extending into said perforations.

4. In a drafting table, the combination of 45 grooved parallel side members and a board extending between them, a roller mounted adjacent one of the ends of the board and having a chain wheel at each end, a second 50 roller adjustably mounted adjacent the other end of the board and having a chain wheel at each end, chains extending around said 55 wheels parallel to each other and to the side members, and paper holders extending across the board and adjustably secured at their ends to said chains.

In testimony whereof I have signed this specification in the presence of two subscribing witnesses.

CARL W. PURKEY.
